Primary Examiner — Lauren D McVey(74) *Attorney, Agent, or Firm* — Fish & Richardson P.C.(57) **CLAIM**

The ornamental design for a capacitor, substantially as shown and described.

DESCRIPTION

FIG. 1 is a perspective view of a capacitor showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof shown with broken line environment that forms no part of the claimed design. The broken lines illustrate environmental features and form no part of the claimed design.
